UNITED STATES PATENT OFFICE.

CYRUS W. BALDWIN, OF YONKERS, NEW YORK, ASSIGNOR TO THE HYDRAULIC ELEVATOR COMPANY, OF CHICAGO, ILLINOIS.

ELECTRO-VALVE-OPERATING DEVICE FOR ELEVATORS.

SPECIFICATION forming part of Letters Patent No. 417,132, dated December 10, 1889.

Original application filed April 19, 1887, Serial No. 235,383. Divided and this application filed September 12, 1888. Serial No. 285,200. (No model.)

To all whom it may concern.

Be it known that I, CYRUS W. BALDWIN, a citizen of the United States, residing at Yonkers, Westchester county, State of New York, have invented certain new and useful Improvements in Electric-Valve-Operating Devices for Elevators, fully set forth in the following specification and represented in the accompanying drawings.

10 The present invention relates to that class of elevators in which the cage is connected with a piston in a cylinder moved by liquid under pressure and provided with a valve-controlling device for directing and controlling the liquid to and from the cylinder; and it consists in certain improvements, fully set forth hereinafter, whereby to facilitate the operation of the apparatus.

In the accompanying drawings, Figure 1 is 20 a sectional elevation of an elevator, showing my improvements in connection with one class of hydraulic elevator; and Fig. 2 is an enlarged detail of the electrical controlling device in the cage. Fig. 3 is an enlarged side 25 view of the brake. Fig. 4 is a section on the line 4-4, Fig. 3.

The cylinder B of the elevator-engine is shown as arranged vertically; but in some instances it may be horizontal, the piston being 30 connected with the rods d, carrying a cross-head supporting a pulley 2, under which pass, the flexible suspensors 3, supporting the elevator-cage E.

5 is the ordinary circulating-pipe, connected 35 with the top and bottom of the cylinder B and in communication with the casing F of a controlling-valve G. A supply-pipe 6 from an upper reservoir 7 or other source of supply also communicates with the valve-casing 40 in a manner well understood.

It is obvious that any other form of elevator-engine may be employed—as, for instance, the one particularly set forth, described, and claimed in an application filed by me April 45 19, 1887, Serial No. 235,383, of which this is a division.

The valve G has usually been operated through mechanical connections from the cage; but the present invention consists, essentially, in employing electrical devices for operating said valve from the cage. These electri-

cal devices consist, essentially, of an electro-motor with connections of any suitable character that will communicate motion from one to the other, and I extend between the motor, 55 generator, and cage flexible electrical conductors and provide the cage with a switch, whereby the current can be directed to the motor to operate it to move the controlling-valve or other stopping and starting device 60 in either direction or arrest the motor and hold the said valve or device in any position, either continuing or arresting the movement of the cage.

Different forms of motors, connections, and 65 switches will suggest themselves to any one skilled in the art.

In that taken for illustration there is provided a hand-lever 29, constituting an electric switch, in connection with the terminals 70 h i of two flexible conductors c d, extending to the battery or generator L and field-magnet of the motor G', and with three contact-buttons e f g, connected with the electrical conductors a b, leading to connections with 75 the armature of the motor. As shown, the armature is a revolving armature carrying a driving-pulley 70, from which a chain or belt 71 leads to the pulley 66, that is provided with a pinion 15, gearing with the rack upon 80 the valve-stem, so that when the motor revolves in one direction it raises the valve, and when in the other direction it reverses it.

As shown in Fig. 2, the lever is shown as being above its normal position to permit the 85 contacts to be better illustrated. When the lever 29 is in a mid-position or horizontal, it is out of connection with all the contacts, and the parts are stationary. When the lever is depressed at the end from a mid-position to 90 bring the pair of contacts h i into contact with the pair of contacts f e, a circuit is completed through the conductors in one direction and the armature is revolved to close the valve, and the parts are kept in this position until the desired amount of movement 95 in this direction is effected. When the valve reaches its proper position, it is arrested and held by simply moving the lever 29 to a mid-position. When the valve is to be opened, 100 the lever is raised from its mid-position to bring the contacts i h into contact with the

contacts *f g*, when the circuit is completed. To impel the armature in the opposite direction, the lever is held in place until the valve is in proper position, when it is shifted and brought to a horizontal position.

In practice I prefer to combine with the valve and its operating connections a brake *I*, of a suitable character, so arranged as to be applied as the liquid is cut off from the cylinder, whereby the cage is clamped in position by the time the valve has been moved to become completely closed, so that it cannot be disturbed by the action of momentum or other source of power.

15 Different forms of brakes and operating means may be employed. In the drawings there is shown a brake corresponding substantially with that set forth in Letters Patent No. 358,322, granted to me February 22, 1887, and hence no detailed description thereof need be here given.

In the present instance the connecting-rod 28 has an elongated slot *y*, receiving a pin 41 upon the hand-lever 29, and the contacts and terminals of the electrical valve-controlling device, when arranged as set forth, cause the direction of rotation of the armature of the motor to be reversed according to the position to which the hand-lever 29 is set by 30 the operator, who brings the lever to a central position and stops the motor as soon as the controlling-valve has assumed a proper position, to be determined by the speed or position of the cage. Springs 60 tend to hold 35 the hand-lever in a central position, with the electrical connection broken and the motor at rest.

When the lever 29 is moved to close the circuit in one direction so as to start the motor to close the valve *G*, the slot *y* will permit the circuit to be completed and the valve to be started before the brake begins to grip the guide 23; but before the valve is completely closed the pin 41 will contact with 45 the end of the slot in the connecting-rod 28, and the brake will firmly grip the guide and arrest the motion of the cage before or at the time of the complete closing of the valve. In the position shown in Fig. 2 the lever has

been moved from a central or stop position 50 over the contacts *f e*, thereby starting the motor and the valve, and the pin 41 has been brought into contact with the end of the slot and the brake-lever has been forced down to release the brake. On again restoring the 55 lever to a central position the circuit will be first completed and the valve started before the brake begins to bear on the brake-bar, and the valve will be brought to a closed position as the brake is fully applied. Like 60 operations take place upon reverse movements of the lever.

The electrical conductors are combined for a greater portion of their length in a flexible cable *K*, supported midway of its length in 65 the well by a bracket 50.

I do not here claim, broadly, an operating device connected to give the stopping and starting device the lead of the brake in applying the latter in either direction, as this 70 constitutes the subject of a separate application for Letters Patent, Serial No. 300,280.

What I claim is—

1. The combination, with an elevator engine, cage, and controlling-valve, of a brake 75 and brake-operating devices carried by the cage, an electromotor, and connections between the latter and the valve, and flexible conductors extending from the motor to the brake-operating devices, and contacts arranged to complete the circuit through said connections in one direction or the other, accordingly as the brake-operating device is shifted, substantially as described.

2. The combination of the cage of an elevator stopping and starting device, motor therefor, brake, and an operating device connected with the brake and embodying a switch constructed to start the stopping and starting device in advance of the application 90 of the brake, substantially as described.

In testimony whereof I have signed my name to this specification in the presence of two subscribing witnesses.

CYRUS W. BALDWIN.
